FORM CRUSHING OF ABRASIVE WHEELS

George F. Eglinton, Detroit, Mich., assignor, by
mesne assignments, to Lincoln Park Industries,
Inc., Lincoln Park, Mich., a corporation of
Michigan

Application November 3, 1943, Serial No. 508,785

7 Claims. (Cl. 125—11)

The present invention relates to improvements in methods and apparatus for the form crushing of abrasive wheels to provide a form generating surface on the grinding face thereof. Such form generated surfaces are employed extensively in form grinding operations, such for example as the grinding of gauge threads, gears or the like, and in all such instances a high degree of accuracy usually maintained within close precision limits is required. In grinding arcuate forms having small radii extreme accuracy in forming the form generating surfaces of the grinding wheel is of particular importance.

The principal object of the present invention is to provide an improved method and apparatus for crushing a form generating surface in the working surface of an abrasive grinding wheel which method is relatively simple to carry out by the use of apparatus herein disclosed which assures the generation of true forms within close precision limits by the use of readily available extruded forms which are continually renewed during the form crushing operation so that a predetermined contour is formed in the grinding surface within close precision limits.

Other objects of this invention will appear in the following description and appended claims, reference being had to the accompanying drawings forming a part of this specification wherein like reference characters designate corresponding parts in the several views.

In the drawings:

Fig. 1 is a fragmentary view partially in side elevation and partially in section showing one form of apparatus embodying the present invention.

Fig. 2 is a plan view partially in section taken substantially along the staggered line 2—2 looking in the direction of the arrows in Fig. 1.

Fig. 3 is a front elevation of the apparatus shown in Fig. 1.

Fig. 4 is a section taken substantially on the line 4—4 looking in the direction of the arrows of Fig. 3.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The apparatus shown in the accompanying

drawings also is a schematic representation of the novel method of form crushing a grinding surface of a grinding wheel which embodies the present invention. The method consists essentially in drawing an elongated form generating wire of desired shape and dimensions over the grinding surface of an abrasive wheel which is held against the form generating wire at a predetermined pressure which may be varied according to the composition of the abrasive wheel but which is sufficient to cause the wire to embed itself progressively into the grinding surface of the wheel without fracturing the said wheel. The abrasive wheel is free to rotate as the wire is drawn over the grinding surface so that the peripheral speed of the wheel is the same as the lineal speed of the wire.

Such a method is carried out satisfactorily by the use of the apparatus shown in the accompanying drawings. This apparatus comprises a fixed table 10 on which is mounted a base 11 having a vertically extending flange 12 on which is secured the yoke of a spooling frame 14 which is mounted for pivotal adjustment relative to the flange 12 and the base 11. The spooling frame 14 includes a vertical bracket 15 on the end of which is mounted a spool 16 of extruded wire 17 of a desired contour and dimension to provide the desired shape in the working surface of the grinding wheel. A second bracket 18 of the spooling frame 14 carries the rotatably mounted idler rollers 19, 20 and 21, which guide the wire 17 over a pressure roller 22 which holds the wire 17 in position for contacting the working surface 23 of an abrasive wheel 24 which is held against said wire 17 at a desired adjusted pressure which is sufficient to cause the wire 17 to become progressively embedded therein to the desired extent during the crushing operation, while permitting the wheel 24 to revolve as the wire 17 is drawn over it.

The roller 22 is provided with wheel supporting flanges 22a and 22b which support the side edge portion of the wheel 24 during the form crushing operation.

The wire 17 is drawn over the working surface of the grinding wheel 24 and the rollers 19, 22, 20 and 21 by the manually actuated reel 25 which is driven by a hand crank 26 and mounted on a third bracket 27 of the spooling frame 14.

Tension on the wire 17 is controlled by a manually adjustable brake on the spool 16, which as shown in Figs. 3 and 4 comprises a friction disc 30 mounted on the face of a plate 31 carried on a push rod 32, which is moved toward or away

from the spool 16 by actuation of the knurled knob 33 keyed to said rod 32. An extending end 34 of the rod 32 extends into the central hole in the hub of the spool 16, and supports one side of said spool for rotation in said bracket 15. The opposite side of said spool is supported for rotation in said bracket by an extending end 35 carried on an axially movable plunger 36 which is movable toward and away from an adjacent face of the spool 16 by actuation of an adjusting collar 37 having a plurality of arcuate slots 38 extending through the periphery thereof and each engaging with one of a plurality of radially extending studs 39 carried on the axially movable plunger 36.

Movement of the adjusting collar 37 thus moves the plunger 36 as may be required to bring the extending end 35 into registration with a central hole in the hub of the spool 16 and thus permits the use of the device with spools of different widths.

The apparatus as here shown is adjusted to crush a straight line circumferential groove in the working surface of the abrasive wheel 24. Such a groove in the wheel 24 will generate a rounded flange or rib on the surface of a work piece which is ground by the wheel 24. In certain uses it is desired to grind a spiral thread with such a surface. To accomplish the grinding of a spiral thread on the work piece, the form generated grinding surface on the grinding wheel extends angularly across the grinding surface of the grinding wheel at such an angle as to generate an inclined spiral thread surface on the work piece. To crush such a form into the grinding surface, the spooling frame 14 is moved pivotally into an adjusted angular position relative to the base 11 so as to hold the wire 17 at an angle to the working surface 23 of the abrasive wheel 24. This angle is determined in such a manner that the groove which is crushed in the working surface 23 of the abrasive wheel 24 will extend both angularly across the working surface as well as circumferentially around the working surface. This is accomplished by loosening the adjusting screw 40 and moving the frame 14 to the desired position as indicated on the calibrated dial plate 41 secured to the base 11. A guide plate 42 is secured to the movable spooling frame 14 and has an arcuate guide slot 43 through which extends the guide pin 44 for guiding the pivotal movement of the frame 14 and also for providing a stop to prevent the movement of said member beyond a predetermined limit.

The operation of the apparatus herein described is as follows: The extruded wire 17 is selected to provide the desired contour to be formed in the grinding surface 23. This form may be circular in cross-section as here shown or it may be triangular, rectangular, hexagonal, or of the like or similar forms in cross-section. The extruded wire 17 is threaded over the rollers 19, 22, 20 and 21 to the reel 25. The spool brake is adjusted to hold the spool 16 against free rotation and the manual crank 26 is turned to rotate the reel 25 and build up the desired amount of tension in the wire 17. The grinding surface 23 of the abrasive wheel 24 is adjustably pressed against the portion of the wire 17 which overlies the pressure roller 22. This pressure is sufficient to cause the wire 17 to become embedded therein during the form crushing operation, but it is not sufficient to cause the wheel 24 to become fractured. The wheel 24 is free to rotate as the wire 75

17 is drawn over its surface 23. Rotation of the reel 25 by actuation of the hand crank 26 draws the wire 17 over the contacting surface 23 of the abrasive wheel 24, which, because of its frictional contact with said wire, is caused to rotate at the same peripheral speed as the lineal speed of movement of said wire. The operator can determine by the amount of force required to operate the hand crank 26, the extent of frictional engagement between the wire 17 and the working surface 23 of the abrasive wheel 24.

10 This permits the operator by suitable adjustment to vary as may be required, the pressures which are exerted by the abrasive wheel 24 on the wire 17. The operation progresses by drawing the wire 17 continually over the working surface 23 until the desired form is generated therein. During this 15 form generating operation, it will be observed that a new wire surface is presented continually to the working surface 23 of the wheel 24 so that at all times a true wire form is available for generating the form in the working surface 23. The selection of various sizes and shapes of extruded wire 17 thus permits the use of the present apparatus and the present method in the formation of various desired types of forms in the working surface 23 of the abrasive wheel 24.

20 The method and apparatus proposed herein thus provides a relatively simple and economical 25 means for generating a desired form in the working surface of a form grinding abrasive wheel and assures the generation of such form therein within close precision limits. The use of a continually renewed crushing form to impart the desired 30 form to the working surface of the abrasive wheel also assures the uniform development of such form in said wheel.

Having thus described my invention, I claim:

1. In the method of crush forming the working surface of a bonded abrasive form grinding wheel, the novel step of continually drawing a selected extruded wire form over the working surface of said wheel to effect the rotation thereof while exerting a controlled pressure thereon 45 sufficient to embed said wire in said wheel but insufficient to cause its fracture.

2. In the method of generating a form in the working surface of a form grinding wheel, the novel step of continually drawing a selected extruded wire form over the working surface of said wheel while exerting a controlled pressure thereon sufficient to embed said wire in said wheel but insufficient to cause its fracture, while permitting rotation of said abrasive wheel at a peripheral speed substantially equal to the lineal speed of drawing said wire over said working surface.

3. An apparatus for generating a form in the working surface of a form grinding wheel and comprising a base, a spooling frame secured thereto and including a spool holding bracket, a roller bracket and a reel bracket, a wire holding spool mounted for rotation in said spool holding bracket, a plurality of guide rollers and a pressure roller mounted for rotation in said roller bracket and a reel rotatably mounted in said reel bracket, and a form generating wire threaded from said spool over said guide rollers and said pressure roller and into said reel, whereby upon rotation of said reel, the wire is drawn from said spool and over said pressure roller.

4. An apparatus as claimed in claim 3 and further characterized in that a wire tensioning

brake is mounted adjacent said spool to exert a braking effect on the rotation thereof.

5. An apparatus as claimed in claim 3 and further characterized in that the spooling frame is mounted for adjustable pivoting relative to said base to vary the direction of the path of said wire angularly relative to said base.

6. An apparatus as claimed in claim 3 and further characterized in that a wire tensioning brake is mounted adjacent said spool to exert a braking effect on the rotation thereof and means are provided to control said brake to vary

the tension on the said form generating wire, and further characterized in that the spooling frame is mounted for adjustable pivotal movement relative to said base to vary the direction of the path of said wire angularly relative to said base.

7. A device as claimed in claim 3 and further characterized in that a hand crank is operatively connected with said reel to effect manual rotation thereof.

GEORGE F. EGLINTON.
